APPARATUS AND METHOD OF MAKING AND
APPLYING BANDS

Johannes Schmiedel, Dresden-A, Germany, assignor to "Universelle" Cigarettenmaschinen-Fabrik J. C. Müller & Co., Dresden-A, Germany

Application May 23, 1934, Serial No. 727,194
In Germany November 22, 1932

13 Claims. (Cl. 131—61)

The present invention has for an object to provide an apparatus and method of applying bands to articles such as cigars and the like.

An object of the invention is to provide a mechanism capable of cutting out bands from a continuous strip of material and then applying said bands about a cigar. A continuous strip or web of material may come directly from a printing or embossing mechanism, or may be provided in a web upon a reel upon which the impressing or stamping has already been applied, and from the reel the web is periodically carried to a die or punch where the band is cut out from the web or strip, and then means are provided for securing such cut out band, and while holding the two ends thereof, transferring the same to a position where it is applied about a cigar which is presented thereto or which may be fed from a cigar making machine.

An object of the invention is also to provide mechanism whereby a strip or web upon which two or more band patterns are provided may be utilized by merely adjusting the reels holding the web so that the web may be passed through the cutting mechanism as many times as desired while removing adjacent bands impressed or printed thereon.

It is an object of the invention to provide mechanism capable of using a strip or web of material since bands of the type operated upon consist only of short pieces of relatively thin paper, and it is obvious that, if these pieces of paper were made separately and then stacked, the removing of a single piece from such stack would be inconvenient and a simple apparatus would not be sufficient. By utilizing a web or strip of material however, in accordance with the present invention, the short strip or band of paper or similar material is engaged while formed and delivered directly to the cigars so that there is no necessity for stacking these short pieces of relatively thin paper and removing them individually from the pile.

It is a further object of the invention to provide an apparatus for carrying out the process wherein use is made preferably of a horizontal layer upon the plate over which the strip or web of material is moving intermittently due to means cooperating with perforations provided in the strip. Preferably a die is provided in the plate for an upper punch and the punched out strip of material is moved from this position to an adjacent position where finished cigars are provided either by an endless conveyor or any other suitable transporting means.

It is a further object of the invention to provide reciprocating means for moving the bands from the cutting out mechanism to the point at which the cigars are presented.

The main object of the invention is to simplify the mechanism for applying bands to cigars or similar articles.

With these and other objects in view which will become apparent as the description proceeds, the invention consists in the method and combination and arrangement of elements set forth below, claimed in the claims and shown in the drawings, in which

Figure 1 is a partial front elevation of a preferred embodiment of the invention,

Figure 2 is a vertical sectional view taken upon the section line II—II of Figure 1,

Figure 3 is a partial side elevation of the structure shown in Figure 2 and looking in the direction of the arrow x,

Figure 4 is a cross sectional view taken on the section line IV—IV of Figure 1,

Figure 5 shows an elevational view of a portion of Figure 1 upon an enlarged scale,

Figure 6 is a plan view of Figure 5,

Figure 7 is a side elevational view of Figure 5,

Figure 8 is a partial plan view with parts shown in section of a portion of the web-feeding mechanism,

Figure 9 is a partial plan view of one form of web,

Figure 10 is a plan view of a portion of a web of modified construction,

Figure 11 is a side elevational view of a modified form of the band retaining mechanism, and

Figure 12 is a plan view of the construction shown in Figure 11.

In the drawings the strip or web 1 upon which are impressed, printed or stamped or embossed the configuration and outlines of the bands, is drawn off the reel 2 which is mounted upon the shaft 3. It is obvious of course that a printing or embossing mechanism may be provided and that a web of paper may be fed to such printing mechanism and then fed to the present apparatus in place of the reel of already printed and embossed material. The shaft 3 is journaled upon the frame wall G' which is vertically positioned upon the machine table G. The web 1 of paper or similar flexible material is guided by means of the guide roller 4 and the conveyor drum 5 over a stamping or punching table 6. In order to prevent any slipping or sliding of the web during the advance, the drum 5 is provided with pins 5' which will engage in the holes 1' 55

furnished in the web 1 as shown particularly in Figures 8 and 9.

The drum 5 is mounted upon an intermittently rotated shaft 7. The intermittent drive mechanism which will be described in greater detail hereafter, is so arranged that after each intermittent movement of the drum 5 the printed or embossed band upon the web 1 will arrive in position directly over the punch or die opening 6.

It is desirable that the drum 5 should always be in engagement with a relatively large length of the web in order to preserve accuracy, and in order to secure this engagement the web is guided over a tension roller 8 mounted on the oscillating lever 10 which in turn is pivotally mounted at 9 upon the frame wall G'. A spring 11 is connected to the lever 10 and urges the roller 8 against the surface of the conveyor drum 5.

From the roller 8 the web 1 is led to a reel 12 mounted upon the shaft 13. The reel 12 is driven by a friction wheel 14 whose shaft 15 is fixed upon the end of the oscillating lever 16. The lever 16 is urged by the spring 17 into contact at all times with the surface of the reel 12.

Mounted upon the shaft 15 of the roller 14 is a spur gear 17' which engages with the spur gear 18 which in turn meshes with the spur gear 19 journaled upon the lever 16. The gear 19 rotates upon the shaft 20 upon lever 16 and meshes with the spur gear 52 mounted upon the shaft 7. The various gear wheels above mentioned are so arranged as to rotate the friction roller 14 and thereby wind the strip or web 1 upon the reel 12 after the same has been released by the drum 5.

The punch plate 6 is provided with a recess 6' with which cooperates the reciprocating punch 21. The shank 21' of the punch 21 is reciprocable vertically in the guide 22. A pin 21' is provided on the shank 21' and the forked end 23' of the oscillating lever 23 engages therewith. The lever 23 is journaled at 24 in the machine frame and is controlled by a control cam to be described below, whenever the printed or embossed band upon the web arrives in the vicinity of the upper punch 21.

Below the punch opening 6' there are provided two U-shaped supports or holders 25 which are attached to a slide 26. The oscillating lever 27 has a forked end 27' which engages with a pin 26' upon the slide 26. The lever 27 is also controlled by a cam member to be described hereinafter, so that the support may be moved into the extended position shown by the dotted lines in Figure 2 and back again. The slide 26 slides on the guide 28.

Located at the ends of the U-shaped supports 25 are control flaps 29 whose pivots 30 are journaled upon the supports 25. At the ends of the pivots 30 are fixed the levers 31 and springs 32 engage the ends of the levers 31 so as to retain the flaps 29 under spring tension both in the extended position shown upon Figure 5 and also in the position shown by dotted lines. The upper punch 21 is provided with spring pins 33 which normally or in the position of rest, project slightly below the surface of the punch. These spring actuated pins have a particular function which will be described below and at the same time prevent the punched out band from adhering to the lower punch surface upon the return of the punch.

The cigars Z which are to be banded are moved by means of the endless chains 34 upon which are mounted the U-shaped supports 35 in which the cigars Z rest. The supports 35 move on the guide

plates 20' supported in any desired manner in the position shown. Above and between the chains is located the apparatus 36 for delivering and applying the bands to the cigars as shown more particularly in Figure 3. This apparatus 36 comprises a slide 37 which is arranged so as to be vertically reciprocated upon a guide rod 38. Mounted on the slide are two levers 39 having their pivot points at 40. These levers 39 are urged by the two springs 41 to swing towards each other and the rollers 39' journaled upon the levers 39 are forced against the guide rod 38. The lower end of the guide rod is curved as shown in Figure 3.

At the free ends of the levers 39 are journaled the rollers 39' over which a band 42 is placed and the ends thereof are attached at 37' to the slide 37 with the interposed springs 43.

The apparatus is driven from the drive shaft 53 which is journaled in the bearing block 54 attached to the machine table G and this shaft carries the loose belt pulley 55 and the fixed pulley 56. A bevel gear 57 is fixed to the shaft 53 and meshes with the bevel gear 58. The bevel gear 58 is mounted upon the shaft 59 which is journaled in the bearing blocks 60 and 61 attached to the table G. Also mounted upon the shaft 53 is the crank lever 62 to which the crank rod 64 is pivotally attached by means of the crank pin 63. The crank rod 64 is pivotally connected by the pivot pin 65 with the double lever 66 to the end of which is pivoted the pawl 69. The pawl 69 is urged by the spring 70 into the teeth of the ratchet wheel 71 which is fixed upon the shaft 67. The ratchet wheel 71 actuates the sprocket wheel 72 also mounted upon the shaft 67. The shaft 67 is mounted in the bearing eye 73 at one end and at the other end in a bearing provided in the frame wall G'. The conveyor chains 34 pass over the sprocket wheels 72 and also the guide wheels 74 which are journaled upon the pins 75.

The shaft 59 also has mounted thereon the cam disks 76 and 77 which have cam grooves in which the rollers 78 and 79 are engaged. The rollers 78 and 79 are rotatably mounted upon the double armed levers 80 and 81 which are in turn pivotally mounted at 82 and 83. Pivotally secured to the free ends of the levers 80 and 81 are the links 84 and 85. The link member 84 is pivotally secured to the arm 87 by the pivot pin 86 and the arm 87 is connected with the lever 84 while the member 85 is connected to the arm 89 by the pin 88 and the arm 89 is connected through the hollow shaft 89' with the lever 44.

The shaft 59 also has mounted thereon the bevel gear 90 which meshes with bevel gear 91 which is journaled upon the shaft 92 provided upon the frame wall G' and in turn is connected with the spur gear 93 journaled upon the same shaft. The spur gear 93 meshes with spur gear 94 which is mounted upon shaft 95 likewise provided in the frame wall G'. Connected with the gear 94 is the check disk 96 which carries the pin 97 which cooperates with the Geneva star-wheel 99 which in turn is connected with the spur gear 52 mounted upon the same shaft 7.

There is also mounted upon the shaft 59 the cam disk 100 with which the cam roller 102 mounted upon the control rod 101 cooperates. The control rod 101 is pivoted at 103 to the two-armed lever 104 and the forked end 101' thereof engages the shaft 59. The double armed lever 104 which pivots about the axis 105 engages with its forked end 104' the pin 106 which is provided

upon the slide 107 which is in turn vertically 5 slideable upon the frame wall G'. An arm 108 which carries the slide 37 is fixed to the slide 107. The slide 37 as set forth above, is mounted vertically slideable upon the guide rod 38. The guide rod 38 is attached to the frame wall G' by means of the arm 109.

There is also mounted upon the shaft 59 the 10 cam disk 110 with which the roller 111 cooperates. The roller 111 is mounted upon the rod 112 whose upper end is pivotally connected to the lever 23 by the pivot pin 113 and the rod 112 is provided with a forked end 112' at its other end which engages about the shaft 59. The 15 cam 114 controls the roller 115 which is mounted upon the lever 27 and the lever 27 is pivotally mounted by means of the pin 116 on the table G.

An adhesive receptacle 118 is mounted upon the wall G' by means of the arm 117 and this receptacle is provided with a glue or paste swab 119 having a shank 119' passing through the bottom of the receptacle 118. At the lower end of the shank 119' there is a pivoted link member 120 which is in turn pivotally connected to the 25 double-armed lever 121 which in turn is pivotally mounted upon the wall G' at 122. The free end of the lever 121 has a roller 123 thereon which is controlled by a cam 124 mounted upon the shaft 59.

30 The means for operating the previously mentioned flaps 29 will now be described. The flaps 29 are controlled by means of a lever 125 which is pivotally mounted upon the shaft 126. At one end a roller 127 is provided which is controlled by a cam 128 also mounted upon the shaft 59. The shaft 126 is mounted in the bearing eyes 129 upon the wall G' and this shaft has secured thereto two arms 130 at the front ends of which are provided the fingers 131. There are also 40 provided upon each arm 130 the upwardly extending pins 132.

The operation of the apparatus above described is as follows. As the web or strip 1 with the printed or embossed bands thereon is carried by the 45 intermittent movement of the drum 5 below the punch 21, the punch 21 is lowered and cuts out the piece or band Zu in cooperation with the punch table 6. The punch 21 after severing the band from the strip or web carries the same into 50 the holder 25 which is held in readiness directly below the punch opening 6'. The punch 21 continues its downward movement to the bottom of the holder 25 as shown particularly in Figure 5 so as to move the spring pins 33 back against their 55 springs. The punch 21 then begins to move upwardly and the ends of the band are maintained and held in the holders 25 by the spring pins 33. As soon as the punch 21 has moved upwardly to about the dotted line position shown in Figure 5, 60 the arms 130 are moved upwardly by the roller 127 as controlled by the cam 128. The pins 132 upon the arms 130 will then contact the levers 31 and thereby swing the flaps 29 into the dotted line position as shown in Figure 5 and the ends of 65 the flaps 29 will thereby come into contact with and hold the ends of the band Zu and retain the same while the punch 21 continues its upward ascent. Then by means of the cam 124 the lever 121 is pivoted against the spring means holding 70 the roller 123 in contact with the cam and the swab 119 which is normally in the adhesive receptacle 118 is moved upwardly into the position shown in Figure 5 by dotted lines.

The swab 119 will thereby move into the depressions 25' provided upon one of the U-shaped sup-

ports 25 and will apply a dab of adhesive to the band Zu. Immediately thereafter the swab 119 is again moved downwardly and the slide 26 carrying the supports 25 is moved by the lever 27 into the extended position as shown in Figure 2. When 5 the supports 25 have reached this latter position the central portion z of the band Zu is directly above the disk. However, before the band Zu is released by the flaps 29 the slide 31 descends so that the rollers 39' and the band 42 positioned 10 thereover will press the band upon the cigar. When the slide 31 continues its downward movement the flaps 29 are swung upwardly, which is accomplished due to the arms 130 describing a downward movement from their central position 15 as shown by the full lines in Figure 2.

The fingers 131 will then contact the ends of the levers 31 and swing these levers 31 into the extended position of Figure 5 so that the flaps will release the ends of the band. As the slide 31 20 continues its downward movement, the rollers 39' will roll over the side portions of the cigars. The function of the band or strip 42 is to make sure that the cigar band Zu is applied perfectly about the cigar Z. As soon as the rollers 39' meet the 25 finger 46 or/and roller 47', the lever 43' is swung to the right whereby one end of the strip or band is folded around the cigar. Then the lever 44 is moved to the left while there is a simultaneous 30 return movement of the lever 43' and thereby the second end which has been provided with adhesive is pressed over the first end folded by the finger 46. As soon as the band has been applied around the cigar in the manner set forth, the 35 lever 44 is again moved to the right into its initial position.

The endless chain 34 is then advanced and the next cigar is carried into the vicinity of the apparatus 36. While the apparatus 36 is operating in combination with the levers 43' and 44, the 40 supports 25 have again been carried back by means of the slide 26 into the dotted line position of Figure 2 for receiving a fresh band.

In the arrangement above described it is assumed that the adhesive receptacle 118 is filled 45 with an adhesive and that the band Zu is provided with dabs of such adhesive at suitable points. It is of course however obvious that during the printing, embossing or stamping of the web 1 with the outlines of the band, that these 50 points can if desired be provided with a fast drying adhesive which afterward need only be moistened. In such a case of course the receptacle 118 would be filled with water.

If as shown in Figures 8 and 9 the strip is provided with two rows of bands Zu then one row is 55 first punched out of the web 1 as shown upon Figure 8. The reel 12 is then changed for the empty reel 2 and the latter is then mounted upon the shaft 13 and the reel 12 upon the shaft 3. In 60 order to carry the second unpunched roll of bands Zu within the vicinity of the punch 21, the shafts 3 and 13 are shifted in their bearings 3' and 13' in the direction of the arrow, as shown upon Figure 8, and they are shifted to such an extent that 65 the spring actuated pins 51 which have hitherto been seated in the notches 3' and 13' will lie in the notches 3' and 13'. The conveyor drum 5 and the correspondingly grooved pressure roller 8 need not be shifted therewith in this case.

70 While the web 1 in its first passage through the apparatus was engaged with the entire series of perforations 1', after the shifting of the shafts, only the two elevated circulating rows of pins 5' as shown in Figure 4 will engage in the two right 75

- rows of holes or perforations 1' of the web. In this case also the pins 5' will engage with the perforations of the strip 1 in order to actuate the drum 5 so that a band may be carried exactly in front and below the punch 21.
- It is also possible as shown in Figure 10, to provide a web 1 with only a single row of bands. In this case the bands can lie longitudinally of the web 1 but as shown in Figure 10, they may also be disposed transversely thereof. In such case of course the conveyor drum 5 must describe or make a correspondingly small advance movement and the web must be advanced at right angles to the advance movement of the cigars.
15. In Figures 11 and 12 a modification is shown in which the supports 25 are not provided with flaps 29. In this modification the flaps 26 are replaced by suction nozzles 133 which are provided at both ends of the U-shaped holders 25 and to 20 which a suction passage 134 is connected. It is of course obvious that the mouthpiece 135 of the suction passage must be connected with some suction producing means such as a fan or the like. In such case a special control or drive is unnecessary because while the band 26 is being applied on the cigar, the ends of the band 26 held firmly by the suction action are simply removed from the vicinity of the nozzle opening 133.
30. The above constitutes the preferred embodiment of the invention, but it is to be understood that all embodiments as will fall within the scope of the following claims are included in such claims.
35. I claim:
1. An apparatus for applying bands comprising a band punching mechanism, means for feeding a web of material containing the bands through said punching mechanism, means for feeding finished cigars and means for applying the bands as punched out by said punching mechanism to said cigars.
  2. An apparatus for applying bands comprising means for cutting out bands, means for feeding a web of material past said cutting out means, conveying means for finished cigars located adjacent said cutting out means and means for applying the bands as cut to said cigars.
  3. An apparatus for applying bands comprising means for cutting out bands from a web of material, means for receiving said bands as cut from said web, means for conveying individual finished cigars, means for moving said receiving means to a position above said conveying means and means for applying said bands about individual cigars.
  4. An apparatus for applying bands comprising a cutting out mechanism, means for feeding a web of material from which bands are to be formed intermittently past said cutting out mechanism, means for receiving said cut-out bands as cut by said cutting out mechanism, means for retaining the ends of said bands upon said receiving means after the cutting out mechanism has ceased to operate, conveying means for individual finished cigars, means for moving said receiving means for said bands to a position adjacent said cigars and means for applying said bands to individual cigars.
  5. An apparatus for applying bands comprising a cutting out mechanism, means for feeding a web of material containing bands intermittently past said cutting out mechanism, means for receiving individual cut-out bands from said cutting out mechanism, means for ap-

plying adhesive to said bands while in said receiving means, means for conveying individual finished cigars and means for moving said cut-out band in said receiving means to a position adjacent said finished cigars and means for applying said bands to said finished cigars.

6. An apparatus for applying bands comprising a vertically reciprocating punch, a reel for holding a web of material containing bands, a rotating drum cooperating with said web of material so as to intermittently feed said web of material past said reciprocating punch, a second reel for winding the web of material after the bands have been cut therefrom, means located below said reciprocating punch for receiving the cut-out band, means for conveying individual finished cigars past said punching mechanism and means for applying the cut-out bands to said cigars.

7. An apparatus for applying bands comprising means for cutting out bands from an endless strip of material, means for feeding finished cigars individually past said cutting out means, reciprocating means for moving each band as cut from said cutting out mechanism to a position adjacent individual cigars and means for applying said bands to said cigars.

8. An apparatus for applying bands comprising means for cutting out bands from a web of material, means for receiving each band as cut, means upon said retaining means for holding the ends of said band therein, means for moving individual cigars past said cutting out mechanism and means for applying said bands to said individual cigars.

9. An apparatus for applying bands comprising means for cutting out bands from a web of material, holders for individually cut bands adapted to receive said bands from said cutting out means, said holders having a suction passage therein, means cooperating with said suction passage for retaining the bands upon said holder after the cutting out mechanism has ceased to operate and means for applying said cut-out bands to a cigar.

10. An apparatus for applying bands comprising a table having a recess, a reciprocating plunger having a plate cooperating with said recess for cutting out bands from a web of material, means for receiving said cut-out bands, resilient means upon said plate for retaining said cut-out bands in said receiving means after said reciprocating plunger has started to recede in order to prevent the adherence of the cut-out bands to said plunger, means upon said receiving means for grasping the ends of the cut-out bands after the resilient means have ceased to operate and means for applying said cut-out bands to a cigar.

11. An apparatus for applying bands comprising means for cutting out bands from a web of material, means for receiving said cut-out bands as cut, means for securely retaining said bands upon said receiving means, means for applying adhesive to one end of said cigar bands while on said receiving means, means for conveying individual cigars past said cutting means, means for moving said receiving means with a band thereon to a position above an individual cigar upon said conveying means and means for applying said band to said cigar.

12. The method of applying bands comprising cutting a band from a web of material, then moving a cigar adjacent the position where said band was cut, then moving said cut band by an

intermediate mechanism from the cutting position to a position above said cigar and then applying the band to said cigar.

- 5 13. The method of applying a band comprising cutting a band from a web of material having impressed, printed or embossed thereon adjacent rows of bands, moving a cigar in proximity to the position where said band was cut, then moving each individually cut band from the

cutting position to a position above said cigar by an intermediate mechanism whereby the feeding of the band for the next cutting step may proceed, then applying said band to a cigar, then repeating the operation until all the bands of one row have been exhausted and then repeating the operation with an adjacent row of bands upon said web of material.

JOHANNES SCHMIEDEL.
